UNITED STATES PATENT OFFICE.

ANDREW J. BONNER, JR., OF PHILADELPHIA, PENNSYLVANIA.

AWNING OR ROOFING.

SPECIFICATION forming part of Letters Patent No. 366,071, dated July 5, 1887.

Application filed July 8, 1885. Serial No. 170,999. (No model.)

To all whom it may concern:

Be it known that I, ANDREW J. BONNER, Jr., a citizen of the United States, residing in the city and county of Philadelphia, State of Pennsylvania, have invented a new and useful Improvement in Awnings or Roofings, which improvement is fully set forth in the following specification and accompanying drawings, in which—

10 Figures 1, 2, and 3 represent plan or top views of pieces of awnings or roofings embodying my invention. Fig. 4 represents a section in line $y-y$, Fig. 2. Fig. 5 represents a section in line $z-z$, Fig. 3. Fig. 6 represents a modification of the parts shown in Fig. 5. Fig. 7 represents a top or plan view of a roof, showing the parts embodying my invention applied thereto. Fig. 8 represents a front view thereof.

20 Similar letters of reference indicate corresponding parts in the several figures.

My invention relates to improvements in corrugated plates for roofs, awnings, &c.; and it consists in the details of construction, as 25 hereinafter set forth and claimed.

Referring to the drawings, A represents sheets or pieces of metal, each having corrugated surfaces B, and a small plane surface between the ends of said corrugations B and 30 the corrugation C, which latter is diagonal to said corrugations B and designed to cover the ridge. The plates are made of various forms, as may be required.

In Fig. 1 is shown a piece designed to be 35 used on the hip or angle of the hip-roofs and similar places, the same having a diagonal edge which is crimped. Two pieces are em-

ployed, the crimp of one piece being placed on and soldered to the crimp of the other piece, thus connecting the two pieces.

The piece shown in Fig. 2 is used in angles or hips and has corrugations formed at angles to each other with a central or dividing corrugation, C. In Fig. 3 are shown two pieces of the same form as in Fig. 1, joined together. 45 In Figs. 7 and 8 the shapes are shown as attached to the roof of a house.

The metal shapes, as described, are ready for application to an awning, roof, &c., by the tinman, roofer, &c., and will be found to 50 be convenient for the purpose intended—viz., the covering and formation of awnings, roofs, &c.,—without necessarily shaping or cutting the same at the place of service.

I am aware that it is not new to form plates 55 having corrugations and also a portion of their surface plane, and such I do not claim.

Having thus described my invention, what I claim as new, and desire to secure by Letters Patent, is—

1. A plate of metal having corrugated surfaces B and a central or dividing corrugation, C, diagonal to the corrugations B, all substantially as described.

2. A plate of metal having corrugated surfaces B, the corrugation C, diagonal to said corrugations B, and a plane surface between said corrugations B and C, all substantially as described.

A. J. BONNER, JR.

Witnesses.
